UNITED STATES PATENT OFFICE

LEWIS T. WILCOX, OF PEEKSKILL, NEW YORK,
PROCESS OF MANUFACTURING WICK-HOLDERS.

1,167,960.

Specification of Letters Patent. Patented Jan. 11, 1916.

Application filed May 25, 1915. Serial No. 30,331.

To all whom it may concern:

Be it known that I, LEWIS T. WILCOX, a citizen of the United States, and a resident of Peekskill, in the county of Westchester, State of New York, have invented certain new and useful Improvements in Processes of Manufacturing Wick-Holders, &c., of which the following is a specification.

The improvements relate to the manufacture of perforated cylinders adapted to contain and carry the wicks of liquid hydrocarbon burners, but may be used in the manufacture of other similar articles.

The wick carriers ordinarily used in oil burners consist of a cylinder of sheet metal within which the wick is secured. This cylinder is provided with perforations adapted to be engaged by the spur of the wick raising device, whereby the wick is raised and lowered. It is common to have the perforations of the wick carrier extend entirely around its circumference and substantially from top to bottom, although it is not necessary to have the perforations extend beyond the zone of engagement between the carrier and the wick raiser, as the oil has free access to the wick on the inside thereof. These carriers are usually manufactured in the following manner: A circular disk of metal is punched out of a sheet of the material, and then drawn or spun into the form of a cylinder with one end closed. This cup is then placed in a perforating machine, and held there ordinarily by having holes punched through the bottom and engaged by suitable projections on the spindle, then rotated and subjected to the action of a reciprocating punch until its sides are perforated to the desired extent. The central portion of the bottom is then punched out, and the portion near the edge of the cylinder turned up to engage the bottom of the wick, which is then placed therein. This process has various objections. A considerable percentage of the blanks are spoiled in the making, and time and materials thus wasted. Furthermore in punching or cutting a round disk from a rectangular sheet of material a considerable part of the material is lost, and of the material of the circular blank with which the operation begins a certain part is wasted when the closed end of the cylinder is punched out. Actual experience has demonstrated that at least thirty per cent. of the material employed in the process described does not enter into the finished article, and is therefore

lost. With the method herein described substantially one hundred per cent. of the material—without deducting for the perforations—is utilized, and a considerable amount is saved also in labor, tools and the overhead incident to extra operations. In addition to this a stronger and more satisfactory carrier is produced. A series of actual manufacturing tests has shown that under the old process an average of fifty-one and one-half square inches of sheet metal are required for each wick carrier three and one-half inches in diameter and two and one-half inches high, whereas by the method herein described less than thirty square inches of material will produce the same article.

In the drawings, Figure 1 is a plan of a rectangular blank of sheet metal after being subjected to the first operation of a process embodying the improvements. Fig. 2 is a longitudinal edge view thereof with the ends in vertical section. Fig. 3 is a plan of the material after it has been subjected to the second operation and formed into a cylinder, the parts adjacent to the secured edges of the metal being shown in horizontal section. Fig. 4 is a vertical medial section of the cylinder of Fig. 3 looking from bottom to top of that figure. Fig. 5 is a view similar to Fig. 4 and of the same parts, after the final operation. Fig. 6 is a view in elevation of one of the wheels employed in turning the edge of the cylinder.

A rectangular blank of sheet metal of length equal to the diameter of the proposed cylinder multiplied by 3.1416 and plus the desired overlap for the seam or joint, and of width equal to the height of the said cylinder plus the turned up lower edge is first produced. This blank is then placed in a suitable die press and stamped and punched into the form shown in Figs. 1 and 2. In this operation the perforations A, B and C are formed and also the curved overlapping seam members E and D, also the annular flange A' surrounding the perforations A. One or more of these operations—as for instance the formation of the perforations A and their surrounding flange—may be performed separately. It will be noted that the seam members D and E at the ends are curved in the primary operation, and that the latter is offset. This curvature is on the radius of the cylinder subsequently formed, so that an even exterior surface will be presented at the seam, and

the offset receives the edge of the other member. The perforations C extend a part of the length of the blank only, but they may extend the entire length of the blank or 5 throughout any desired section or part thereof.

In the next operation the strip of material is doubled, preferably over a suitable form and the ends brought together so that 10 the parts D and E overlap and the flanges A' enter the holes B. The inner edges of the flanges A' are then upset by a hammer striking the exterior of the cylinder at this point and compressing the flange between it 15 and the anvil inside, or by other suitable means. In this manner a seam is formed and the overlapping parts secured together, without the employment of rivets or other fastening means, the upset or clenched edges 20 A'' binding the parts securely and reinforcing the edges of the openings.

In the next operation the lower edge F of the cylinder formed in the preceding operations is turned up, as shown in Fig. 5, 25 by means of grooved wheels such as the wheels G illustrated in Fig. 6, or by other suitable means. This completes the structure. Before this last operation, however, the cylindrical wick is placed inside the cylinder so that when the lower edge F is 30 turned up it will bind the bottom edge of the wick and hold it securely in place. It will be understood that when the wick is thus secured within the carrier it is allowed 35 to extend a sufficient distance above the carrier to span the space between the wick raising device and the combustion zone of the burner.

The advantages of the process herein 40 described will be apparent to those skilled in the art. One of these advantages resides in the fact that by forming the perforations and annular flanges and uniting them in the manner described the diameter of 45 the cylindrical carrier is fixed with a degree of accuracy and precision not obtainable by the use of ordinary rivets or by folding the edges of the sheet of metal or by other methods. Another advantage re- 50 sides in the fact that the finished article presents a smooth exterior so that it will fit exactly in the wick tube and not cause any

friction or binding. The slight projection on the inside at the seam will merely cause an indentation in the wick, and will give 55 rise to no disadvantages.

What I claim is:

1. The method of making cylindrical carriers and the like, which consists in forming 60 openings in both ends of a substantially flat blank, forming upstanding integral rivet flanges on the edges surrounding the openings at one end of said blank, bending the blank to tubular form, passing the said flanges through the openings of the opposite 65 end and upsetting said flanges snugly over said other end.

2. The method of making cylindrical carriers and the like, which consists in forming 70 a zone of perforations in and transversely of a substantially flat blank, forming openings in both ends of said blank, and producing upstanding integral rivet flanges around the openings at one end from the metal displaced in forming said openings, bending 75 the blank to tubular form, passing the said flanges through the openings of the opposite end, and upsetting said flanges snugly over said other end.

3. The method of making cylindrical carriers and the like, which consists in forming 80 a zone of perforations in and transversely of a substantially flat blank, producing flanges at the ends of said blank in a longitudinal curvature that is substantially the 85 curvature of the completed carrier, forming openings in said flanges, the openings at one end being of greater diameter than those of the other and the metal displaced in forming said other openings constituting 90 circular upstanding rivet flanges that snugly pass through the larger openings at the opposite end, bending the blank to tubular form, passing the said flanges through the 95 openings of said opposite end, and upsetting said flanges over said opposite end.

Witness my hand this 14th day of May, 1915, at the city of New York, in the county and State of New York.

LEWIS T. WILCOX.
